COMBINED FAUCET FIXTURE AND HANDLE

Harper Landell, Whitemarsh, Pa., assignor to Speakman
Company, Wilmington, Del.

Filed Nov. 21, 1963, Ser. No. 77,537

Term of patent 14 years

(Cl. D91—3)

FIG. 2.

FIG. 3.

FIG. 4.

FIG. 5.

The dominant features of my design reside in the portions shown in full lines.

I claim:

The ornamental design for a combined faucet fixture and handle, as shown and described.
